UNITED STATES PATENT OFFICE.

FREDERIC D. CLEMENT, OF WINCHESTER, AND JOHN A. WHEELER, JR., OF MEDFORD,
MASSACHUSETTS, ASSIGNORS TO WHITNEY MACHINE COMPANY, OF WINCHESTER,
MASSACHUSETTS, A CORPORATION OF MASSACHUSETTS.

LEATHER-WORKING MACHINE.

Application filed March 6, 1924. Serial No. 697,225.

This invention relates to machines for operating on leather, more especially for putting out or setting. For best results the hide should be stretched from the back toward the belly and in inclined directions toward the shoulders and flanks. Machines hitherto used to effect this operation have not been so constructed that the stretch could be effected in the most advantageous manner, and it has usually been necessary to run the skin through the machine twice in order that all of it may be treated. There has also commonly been no means provided for securely holding the leather in position for the treating tools to operate thereon so that often the skin has not passed through the machine in the intended or proper manner. Furthermore it has generally been impossible for the operator to see the skin while it is being operated upon so that faulty operation of the machine is not noticed until damage has been done.

According to this invention, therefore, the side of leather is placed over a bolster, the upper edge of which engages the hide along a line substantially parallel to and closely adjacent to its back edge and the machine is started. The bolster carrying the hide then tips backward somewhat and a clamp closes down on the upper end of the side of leather to hold it in position on the bolster. The bolster with the hide extending down over its front face in full view and in position to be easily manipulated by the operator passes upwardly back of the leather working mechanism, comprising revolving fluted rollers and a pressure plate which act to stretch the leather in the proper directions to remove substantially all the liquor therein and set the grain. In order to decrease the extent of motion necessary for the action of the bolster, the rollers and pressure plate are caused to traverse in the opposite direction to the bolster, but throughout this motion the portions of the leather untreated at any particular time are easily accessible to examination and manipulation by the operator. This double motion also permits the rollers and pressure member to act as a counterbalance for the weight of the bolster so that there is a material saving in the power required for the treating operation. As soon as the parts have traversed sufficiently, the pressure therebetween is released, the bolster

and treating mechanism are returned to their former positions, the clamp being removed from the bolster, and the machine stops automatically so that the treated hide may be removed and an untreated hide placed in position.

For a more complete understanding of this invention, reference may be had to the accompanying drawings in which—

Figures 1 and 2 are right and left hand elevations, respectively, of the machine.

Figure 3 is a fragmentary front elevation.

Figures 4 and 5 are vertical sections on lines 4—4 and 5—5, respectively, of Figure 3.

Figure 6 is a fragmentary rear elevation of the right hand end portion of the machine.

Figures 7 and 8 are somewhat diagrammatic details showing certain of the parts during the operative traverse of the bolster and after the end of such traverse, respectively.

Figure 9 is a fragmentary elevation showing the manner in which the tilting of the bolster at the starting and stopping of the machine is effected.

Figure 10 is a detail of the clutch and brake mechanism.

Figure 11 is a longitudinal section through the adjustable toggle.

Figure 12 is a detail showing the driving connections to a rear fluted roller.

Figure 13 is a detail showing some of the parts shown in Figure 5 in different relative positions.

Figure 14 is a detail of a cable connection.

Figures 15 and 16 are details in elevation of a fluted roll and a pressure plate, respectively.

Figure 17 represents a side of leather showing the directions of the stretching forces applied thereto in the operation of the machine.

The machine comprises a pair of spaced U-shaped lower side frames 1 and 2 and superposed on each of these side frames are upper inverted U-shaped side frames 3 and 4 bolted thereto. The lower side frames are shown as spaced apart by a channel beam 5 adjacent their lower edges, a channel beam 6 at their upper rear portion and a tubular connector 7 in the lower rear corners. The upper frame members are spaced by means of a pair of channels 8 and 9 at the forward

and rear edges of these members. The channel member 5 is fixed to each lower side frame member by means of a pair of brackets 10. These brackets 10 are each formed with a vertical slot 11 therethrough, each slot forming a guideway for the lower end of a track beam 12 hung on a pivot shaft 13 extending inwardly adjacent the upper rear portion of the top side frames 3 and 4. 10 Each track beam has a guide rail portion 14 on its forward face to slidably receive a carriage 15. At the upper edge of each carriage is an outwardly extending lug 16 perforated for the reception of a bolt 17 which 15 is adjustably fixed therein by means of nuts 18 at either end of the lug and a lock nut 19 at one end. To this bolt 17 is fixed the lower end of a chain 20 which passes over a large chain wheel 21 fixed to a shaft 22 20 journaled in a bearing 23 at the upper end of the corresponding side frame members 3 or 4. The opposite end of each chain 20 is made fast to a carriage 25 supporting the leather working instrumentalities, this carriage sliding on an inclined way 26 made fast to the inner face of the corresponding lower side frame members 1 or 2, the two ways 26 being in opposed relation on the two frame members. The guideways 26 25 are parallel with the track beams 12 when the lower ends of these track beams are swung forwardly as will be later described. In order that the carriages 15 and 25 may be given positive movements in opposite directions, the upper end of a cable 27 is fixed to each carriage 25, these cables passing about a pair of sheaves 28 adjacent the lower forward ends of the side frame members 1 and 2 and then upwardly where they are each fixed to a sheaf 29 fixed on the shafts 22 as best illustrated in Figure 14.

Each carriage 15 above referred to has pivoted thereto at 30 a bolster 35 over which the leather to be treated is placed. In order 45 to resist the heavy pressure to which the bolster is subjected by the leather working instrumentalities it is very rigidly constructed. As shown best in Figures 4 and 5 it comprises a series of I beams 36 held in 50 parallel spaced relation by spacers 37 placed therebetween, tie bolts 38 passing through the beams and spacers to hold the parts assembled. A plank facing 39 is fixed to the forward face of these elements, this being 55 covered by a suitable surfacing blanket 40 which covers the entire forward face of the bolster and is brought down in inclined position as shown at 41 back of the narrow rounded upper edge 42. At the lower edge 60 of the bolster at each end is an extension 45 carrying a roller 46 which is adapted to ride on the forward face of a flange 47 extending inwardly from the adjacent track beam 12 between its front and rear faces and substantially parallel thereto. When the car-

riage 15 is near its lower limit of motion the rollers 46 are below the lower ends of the flange 47 and hence are not guided thereby. The pivots 30 of the bolster, however, are formed as trunnions fixed thereto and outwardly of their bearings in the carriages 15 each has fixed thereto an arm 50 having a roller 51 journaled at its lower end. This roller may pass between spaced jaws 52 and 53 of a bracket 54 pinned at one end as 75 at 55 to a boss 56 extending from the upper side of the corresponding lower frame members 1 and 2 and by a bolt at its other end thereto as at 57. The space between the guide jaws 52 and 53 is so shaped that when the roller 51 is at the lower end thereof the bolster is rocked to substantially vertical position as shown in Figures 1, 2, 4, 5 and 9. As the carriage 15 is moved upwardly on the track beams 12 the rollers 51 are brought into engagement with the upper portions of the jaws 52 and 53 and are moved forwardly so as to swing the upper edge of the bolster rearwardly so that its forward face is brought substantially parallel to the forward faces of the track beams 12, this being shown best in Figure 9. In this position of the parts the rollers 46 carried by the bolster are in position to engage the forward faces of the flanges 47 to be guided thereby on further movement of the bolster to retain the bolster in this inclined position.

Pivoted at the upper edge of each carriage 15 at 60 between the track bars 12 is a lever bracket 61 having an inclined upper face 62 to which is fixed a plate 63 joining the two bracket arms, this plate having its lower edge 64 concaved and covered with a suitable surfacing 65 to form a clamping member engageable with the upper rounded edge 42 of the bolster. As the bolster swings rearwardly the rear portion of this rounded edge 42 engages the concaved member 64 and rocks the clamping member down into engagement with the leather extending over the upper edge of the bolster. This rocking motion of the lever bracket 61 is resiliently opposed so that the leather may be firmly clamped. For this purpose there is pivoted to each bracket lever backwardly of the pivot 60 at 67 a link 68 to the end of which is fixed a threaded bar 69. On the threaded portion of this bar is a nut 70 and surrounding this bar between this nut and a lug 71 on the carriage 15 is a coil spring 72. This spring acts to force the bar upwardly so that when the bolster is in its tilted position, the clamping bar 63 is pushed firmly against the side of leather extending over the edge 42 of the bolster, this position of the parts being illustrated in dotted lines in Figure 9.

During the upward movement of the bolster and the clamp, which is effected by the upward sliding of the carriages 15, the

lower ends of the track beams 12 are held forwardly so that the work on the bolster is in position to be acted upon by the leather working instrumentalities carried by the carriages 25. For this purpose a toggle mechanism is employed, which when in straightened position holds the lower ends of the track beams in their forward position. This toggle mechanism is shown in detail in Figure 11 and its straightened and broken positions are illustrated best in Figures 7 and 8. The track beams 12 have rearwardly extending lugs 80 near their lower ends to which are pivotally connected the forward ends of toggle links 81. To the rear end of the links 81 are pivoted the toggle links 82 and the rear ends of these toggle links are fixed to a rock shaft 83 extending transversely of the machine and journaled in the lower side frames 1 and 2. By rocking this shaft it is evident that the links 81 and 82 may be straightened to move and hold locked the lower ends of the track beams in their forward positions, or by rocking in the direction of the arrow *a* in Figure 8, these links are brought out of substantial alignment and the track beams are brought to their rearward position within the guides 11. As shown in Figure 11 the link 82 has a pair of integral stop lugs 85 and 86 which may engage on lugs 87 and 88 on the link 81 to limit the relative pivotal movements of these links. It will also be noted that the link 82 is formed in two telescoping sections 90 and 91 which are held together in adjusted position by bolts 92 which pass through slots 93 in the section 91 and holes in the section 90. The rear end of section 91 is provided with a seat 94 for the reception of the shaft 83 and a cap plate 95 completes the clamping engagement for this shaft. Through ears 96 of this cap plate are passed adjusting bolts 97 having lock nuts 98 thereon, the forward ends of these bolts engaging the end of the section 90 for the purpose of adjusting the distance between the shaft 83 and the pivot 89.

Outwardly of the lower frame member 1 the shaft 83 has fixed thereto an arm 100, the outer end of which is pivoted to the lower end of a rod 101. This rod passes adjacent to the upper end of the machine where it is pivoted at 102 to the intermediate portion of an arm 103 fulcrumed at one end at 104 in a fixed bearing 105. The free end of the arm 103 is positioned within the path of a roller 106 journaled on a pin 107 extending outwardly from a gear wheel 108 carried by the left hand shaft 22. This shaft 22 has fixed thereon outwardly of the gear 108 a hooked arm 109, which may engage beneath the extended end of the pivot 102 as shown in Figure 8. On rotation of the gear 108 in a direction to permit the carriages 15 to descend the roller 106 en-

gages the free end of the arm 103 as shown in Figure 2, depressing the rod 101 and rocking the shaft 83 in a direction to straighten the toggle links 81 and 82 so that the lower ends of the track beams 12 are moved forwardly. On rotation of the gear 108 in the opposite direction the arm 109 comes to the position as shown in Figure 8, where it engages beneath the pin 102 and raises the rod 101, breaking the toggle and moving the lower ends of the track beams 12 rearwardly. This later action is effected when the bolster has reached its desired upper limit of motion as will later be described. The toggle may also be broken by the operator at any time during the upward stroke of the bolster. For this purpose a treadle 110 is fulcrumed at 111 to the frame member 1, the rear end of this treadle passing beneath the pivotal connection of the rod 101 with the arm 100. By exerting pressure on the outer end 112 of this treadle it is evident that its inner end will be raised and the arm 100 rocked to break the toggle. The gear 108 above referred to (Figure 2) meshes with a pinion 115 fixed to a shaft 116. This shaft extends across the width of the machine and carries adjacent its opposite end (see Figure 1) a similar pinion 117 meshing with a gear 118 carried by the right hand shaft 22. By this means the shafts 22 are caused to rotate in unison so that the carriages 15 are caused to move simultaneously and both ends of the bolster are given the same raising and lowering movements. For the purpose of rotating the shafts 22 to effect traverses of the carriages 15 and 25 the shaft 116 is arranged to be driven. At its right hand end as shown in Figures 1 and 3 this shaft 116 carries a gear 120 with which meshes a pinion 121 journaled on a shaft 122 which is fixed in a bearing 123 (Figure 4) at the rear of the upper frame member 4. Fixed to rotate with the pinion 121 is a sprocket wheel 125 over which passes a driving chain 126. The lower portion of this chain passes about a sprocket wheel 127 on a jack shaft 128 and at an intermediate point it may pass over an idler sprocket wheel 129. At 130 is shown the main drive shaft of the machine carrying a drive pulley 131 at its right hand end. This drive shaft (Figure 6) extends through a journal in the side frame 2 and its opposite end is journaled in a bearing 132 in an intermediate frame member 133 fixed at its upper end to the cross frame member 6 and at its lower end to the tubular connector or pipe 7. This shaft 130 carries a pair of pinions 135 and 136. The pinion 136 meshes with a gear 137 journaled on the shaft 128 and the gear 135 meshes with an intermediate pinion 138 which meshes with a gear 139 also journaled on the shaft 128. Fixed to rotate with

the gear 137 is one element 140 of a friction clutch and fixed to rotate with the gear 139 is a similar element 141 of a second friction clutch. Between these clutch elements 140 and 141 is a clutch collar 142 slidably keyed to the shaft 128 (see Figure 10). The opposite ends of this clutch collar are operatively connected to the expanding clutch elements 143 and 144, these expanding elements cooperating, respectively, with the clutch elements 140 and 141. By moving the collar 142 axially of the shaft 128 from its mid position, one or the other of these expanding clutch elements 143 and 144 will be brought into clutching relation with its mating clutch member while in the mid position of the collar 142 both are out of clutching engagement. It will be seen that through the gear connection of the drive shaft 130 directly to the clutch element 140 this element is given a rotational direction opposite to that of the shaft 130 while the clutch element 141 is given a movement in the same direction as the shaft 130 due to the idler gear 138 interposed between the gears 135 and 139. It will also be noted that the gear 139 is smaller than the gear 137 thus causing the clutch element 141 to rotate at a slower speed than the clutch element 140. This slower speed clutch is operative during the upward movement of the carriages 15 and the downward movement of the carriages 25, which is the operative motion of the machine, while the opposite more rapid direction of motion is idle as will later be described. The collar 142 is moved axially of the shaft 128 by means of a shipper arm 145 (Figure 10) pivoted at 146 to a collar 147 journaled on the collar 142 between the flanges 148 and 149. The outer end of this shipper arm 145 is fixed to a vertical shaft 150 which extends substantially the full height of the machine, being journaled in a bearing 151 fixed to the pipe 7 at its lower end in a bearing 152 fixed to the cross beam 6, and in a bearing 153 fixed to the cross beam 9. This shaft 150 may be rocked by the operator to control the machine, for this purpose a lever 154 being fixed thereto at its rear end and extending forwardly where it may be grasped by the operator in front of the machine (see Figure 5).

In order that the motions of the carriages may be stopped whenever the clutch collar 142 is moved to its mid position to disconnect both clutches, an automatically acting brake mechanism has been devised. Referring more particularly to Figures 6 and 10, it will be seen that the shaft 150 has fixed thereto an arm 160 having a cam face 161 at its outer end formed with a central depression 162 and arcuate portions 163 at opposite sides of this depression. Riding on this cam face is a roller 164 carried at one

end of a lever arm 165. This lever arm is pivoted at 166 to a bracket 167 carried by the frame member 6, and extending through a slot 168 in the opposite end of this lever arm 165 is the outer end of a rod 169 which passes through the bracket 167 and the frame member 6 and is fixed at 170 to one end of a brake band 171 partially enclosing a brake drum 172 fixed to the shaft 128. The opposite end of this band 171 is brought up and fixed at 173 to the outer face of the bracket 167 as shown in Figure 6. A spring 175 surrounds the rod 169 between the outer face of the bracket 167 and a washer 176 held in adjusted position on the rod 169 by means of a nut 177 threaded thereon. This spring urges the rod 169 rearwardly to cause the brake band 171 to be tightened about the drum 172, thus applying the brake. The lever arm 165, however, bears against a washer 178 held in position by a pair of lock nuts 179 threaded on the rod 169 outwardly of the nut 177 and when this lever arm 165 is rocked to force its end against the washer 178 the rod 169 is pushed forwardly, releasing the band 171 from the brake drum. When the roller 164 on this lever engages in the notch 162 of the cam face, the opposite end of this lever arm is free to be moved rearwardly by the spring 175 and the brake band is tightened about the drum, this position of the parts being when the clutch collar 142 is in its mid position. When this collar is moved to either clutching position one or the other of the arcuate portions 161 and 163 of the arm 160 engage the roller 164, whereupon the lever arm 165 is rocked to apply pressure against the washer 178 and move the rod 169 forwardly to release the brake. It will thus be seen that whenever either clutch is in operative position the brake is released, and when both clutches are disconnected, the brake is applied.

Provision is also made for the stopping of the machine automatically after a single up and down traverse of the bolster. For this purpose the lower end of one of the carriages 15, as shown in Figure 5, has journaled thereon, a cam roller 185, which when the carriage is in its lowest position, impinges on a dog 186 pivoted at 187 on the bracket 184 at the inner side of the frame member 2, this end of the dog being urged upwardly by means of a spring 188 fixed thereto below its pivot and to a fixed point of the machine. The bracket member 184 has an upstanding guide lug 189 in which is slidably the forward end of a rod 190. This rod has adjustably fixed thereto a collar 191 having a cross pin 192 therein which may be contacted by the rear edge of the dog and moved rearwardly when this dog is depressed by the engagement of the roller 185 thereon. The rear end of the rod 190 is pivoted at 193 to the lower end of

an arm 194 journaled on the shaft 83. The upper end of this arm 194 is formed with a hooked portion 195 in which engages a pin 196 extending laterally from an arm 197 fixed at the forward end of a link 198. The rear end of the link 198 is bifurcated at 199 and between the forks is pivoted one end of a link 200, the other end of this link being formed as a sleeve 201 which is fixed 10 to the shaft 150. As the carriages 15 reach their lowermost positions, therefore, the dog 186 is rocked, moving the rod 190 rearwardly and causing the link 198 to be drawn forwardly, rocking the shaft 150 to bring 15 the clutch collar 142 to its mid position whereupon the machine stops. This arm 194 is positioned adjacent a segment 205 fixed to the shaft 83, the member 197 extending through a slot in an upper convexed 20 wall member 206 thereof and having a laterally extended portion 203 riding on its upper surface. At the forward end of this wall member is an upstanding lug 207, which when the toggle is broken, is swung 25 rearwardly into contact with the upper end of the element 197. This breaking of the toggle takes place when the carriages 15 are near their upper limit of motion and the impingement of the lug 207 causes the 30 lug 198 to be pushed rearwardly (see Figure 13), rocking the shaft 150 in a direction to unclutch the elements 141 and 144 and clutch the elements 140 and 143, thus reversing the direction of rotation of the shaft 35 128 and consequently starting the carriages 15 on their downward motion. Before the carriages have reached their lowest position, but after the bolster has been removed from operative relation to the leather working instrumentalities, the roller 106 has engaged the arm 103 and straightened the toggle, thus rocking the segment 205 forwardly so that the lug 207 is free from the element 197, the parts then being in position 40 so that when the rod 190 is moved rearwardly the member 197 may be drawn forwardly by the rocking of the arm 194 to its mid position (as shown in Figure 5) where both clutches are unclutched and the 45 machine is stopped.

The leather working mechanism comprises instrumentalities carried by the carriages 25 as follows: At each end of the carriages are pivoted at 220 and 221 adjacent ends of arms 222 and 223, the outer ends of these arms have pivotally connected thereto links 224 and 225 to which are fixed the rear ends of threaded rods 226 and 227. Each rod has threaded thereon an abutment nut 228 against which bears a washer 229. Against this washer presses one end of a spring 230 surrounding the rod and this spring bears at its outer end against a lug 229^a extending outwardly from the carriage. A washer and nut 231 on the outer

face of each lug 229^a form stops to limit the rearward motions of the arms 222 and 223, and the springs 230 act to swing the arms rearwardly as far as is permitted by these stops. These arms 222 and 223 each 70 have enlarged openings 235 therein (see Figure 1) in which are pivoted on axes lengthwise of the arms, bearings 236 in which are journaled shafts 257 and 268 on which are fixed fluted rollers 238 and 239. 75 The flutes of these rollers extend in opposite spiral directions from their centers of length as illustrated in Figures 3 and 15, thus forming a series of spiral ribs 240 thereon which may engage the leather extending down the forward face of the bolster when in operative relation thereto.

These rollers are rotated and for this purpose driving connections shown in Figures 1 and 2 are provided. Outwardly of the side frame 2 the drive shaft 130 has pivoted thereon a link 250 and in the outer end of this link is a shaft 251. On this shaft is journaled a pair of sprocket wheels 252 and 253. Sprocket wheel 252 has a sprocket chain 254 passing thereover which also passes about a sprocket wheel 255 fixed to the drive shaft 130. Pivoted on the shaft 251 is the lower end of a link 256, the upper end of which is pivoted on a shaft 95 257 carrying the lower roller 238. Outwardly of this link 256 the shaft 257 has fixed thereto a sprocket wheel 258 over which passes a chain 259 which also passes over the sprocket wheel 253. In this construction it is evident that the shaft 257 is driven from the main drive shaft regardless of the position of the carriages 25, the links 256 and 250 maintaining the driving chains in proper driving relation at all times. At the opposite end of the shaft 257 is fixed a sprocket wheel 265 over which passes a chain 266 (see Figure 2) which engages over a sprocket wheel 267 fixed to a shaft 268 carrying the upper fluted roller 100 239. The sprocket wheel 265 is preferably of greater diameter than the wheel 267 in order to drive the upper roller faster than the lower roller and give a burnishing effect 105 to the leather. The upper roller may also have more flutes than the lower roller. 110

Between the rollers 238 and 239 is a ribbed pressure plate 270, the ribs 271 thereon being in diagonal formation as shown in Figure 16, the direction of the diagonal reversing at its center of length. This pressure plate may comprise a channel bar 272 to which the ribs 271 are applied, as shown these ribs comprising plates 273 fixed to the outer face of the channel 272 by means of 120 angles 274. This channel is fixed at each end to the rear end of a cast block 275 having strengthening and stiffening ribs 276 thereon (see Figures 3, 4 and 5). Each of these blocks 275 is slidable on a carriage 125 130

and each has a pair of laterally extending lugs 277, while rearwardly of these lugs are fixed lugs 278 on the carriages 25 through which are threaded abutment screws 279 to fix the rearward limit of motion of the pressure plate. The pressure plate is urged inwardly toward these bolts by means of springs 280 reacting between the lugs 277 and cup plates 281 rotatably carried at the inner ends of adjusting bolts 282 threaded through cap plates 283 on the carriages 25. It will be seen, therefore, that both the rollers and the pressure plate are urged rearwardly to an adjustable extent so that when the bolster carrying the leather thereon passes upwardly with the track beams 12 swung forwardly they press against the leather and work it away from the upper edge where it is clamped to the top edge of the bolster. Due to the diagonal arrangement of the ribs on the fluted rollers and the pressure plate, the pressure is exerted downwardly and diagonally outwardly in the manner illustrated by the arrows *b* in Figure 17, the line of clamping of the leather being shown by the dot and dash line *c—c*. This line is substantially parallel to and closely adjacent the back edge of the side of leather so that the pressure is exerted toward the belly and the shoulders and flanks, which is the direction in which the leather should be stretched and the grain laid.

A narrow edge of the leather may extend down the inclined rear upper face 41 of the bolster and if desired mechanism may be employed for treating this portion of the leather at the same time that the portion extending down the forward face of the bolster is being treated. Such mechanism is shown best in Figures 4 and 12. Referring to these figures, a bracket 300 is carried by the beam 5, this bracket having a pair of upwardly extending spaced arms 301 within which is fixed a shaft 302. Pivoted on this shaft between the lugs 301 is a rigid upwardly extending arm 304 at the upper end of which is journaled a shaft carrying a fluted roller 305 similar in construction to the fluted rollers 238 and 239. It will be understood that there is a corresponding arm 304 at the other side of the machine for supporting the roller 305. Fixed to each carriage 15 is a member 306 having a cam path 307 therein within which rides a roller 308 carried near the upper end of an arm 309 also journaled on the shaft 302 within the bifurcated lower end of the arm 304. Beneath the roller 308 pivoted at 310 is the forward end of a rod 311 which extends through the arm 304 and carries thereon a spring 312 bearing between a washer 313 resting against the face of the arm 304 and a washer 314 held in position on the rear end of the rod 311 by means of a nut 315. This spring acts

to urge the arm 304 toward the arm 309 as far as is permitted by abutment screw 316 threaded through the arm 304 and against which a lug 317 on the arm 309 impinges. This acts to press the roller 305 against the leather extending down the inclined face 41 of the bolster after the bolster has been tipped back and the work has been clamped thereon by the clamping plate 63. The cam path 307 is so shaped that this roller is brought down against the face 42 by the time the bolster has raised sufficiently to be fully clamped, as shown in dotted lines in Figure 7. As the bolster moves further upwardly the roller is caused to move down this inclined face and off the edge thereof at which time it reaches the lower vertical portion of the slot 307 which holds it away from the rear face of the bolster. This roller 305 is rotated. For this purpose a sprocket wheel 320 is fixed to rotate therewith at one end over which passes a sprocket chain 321 which passes about a sprocket wheel 322 journaled on the shaft 302 at one side of the machine. Fixed to rotate with this sprocket wheel 322 is a similar wheel 323 over which passes a chain 324 which engages a sprocket wheel 325 on a shaft 326. This shaft carries a gear 327 meshing with a pinion 328 on the main drive shaft 130. It is only necessary to use sprocket wheels 322 and 323 at one side of the machine.

When the machine is at rest the bolster 35 is at its lower position extending substantially vertically. The side of leather to be treated is then thrown over its upper edge, back uppermost, the line *c—c* of Figure 16 illustrating the portion which lies over the rounded upper edge of the bolster. The clutch then having been thrown to the right by actuation of the lever 154, to engage the clutch 141, the carriages 15 are caused to move up the track beams 12 and the carriages 25 are caused to be lowered. As soon as the carriages 15 start to rise the bolster tips rearwardly, its upper edge 42 engaging the clamp 63 and the bolster taking the position parallel to the forward face of the track beams as illustrated in Figure 7. It will be understood that at this time the toggle links 80 and 81 are straightened so that the lower ends of the track beams are pressed forwardly. As soon as the bolster has reached this position and the work has been clamped, its supporting rollers 46 engage the track flanges 47, thus firmly holding the bolster in parallel relation with the track beams. The bolster then rises and the carriages 25 carrying the leather working instrumentalities lower so that the roller 238, then the pressure plate, and then the roll 239 engage the leather, press it against the bolster, and act to stretch it downwardly and laterally over the forward face of the bolster, the inclined position of the ribs on these parts act-

ing to give the lateral components to the thrust. At the same time the rear roller acts on the leather extending rearwardly from the clamp and stretches it away from the clamp 5 and outwardly as shown by the arrows *d* in Figure 17. As soon as the bolster has reached the desired upper limit of its motion and the leather has been worked upon by the rollers and pressure plate, the arm 109 of the shaft 22 raises the rod 101 as illustrated in Figure 8 and breaks the toggle so as to pull the lower ends of the track beams rearwardly as shown by the arrow *e*. This moves the bolster 35 away from cooperative 10 relation to the instrumentalities carried by the carriages 25. The rocking of the shaft 83 also acts through the segment 205 to push the rod 198 rearwardly, rocking the shaft 150 and causing the clutch connections to 15 be reversed so that the clutch 140-143 now becomes effective and the carriages 15 and 25 are given their reverse direction to traverse at a higher rate of speed than their working traverses. As the carriages 15 approach their lowest position the bolster is 20 caused to again assume its vertical position with the material unclamped and the lower ends of the track beams are moved forwardly again by impingement of the roller 106 on the arm 103 straightening the toggle links. Just before the carriages 15 reach their lowest positions the roller 185 strikes the dog 186, causing the clutch 140-143 to be unclutched, bringing the clutch collar to its 25 neutral position and permitting the brake to be applied so that the machine stops.

It will be seen that as the bolster moves up its forward face is accessible for the operator to stretch and pull the leather as he may see fit and to closely observe the manner in which the leather is approaching the working instrumentalities. Should the action be unsatisfactory at any time he has only to step on the treadle 110 to effect breaking of 30 the toggle and to move the track bars back so as to bring the bolster out of cooperative relation with the rollers and to reverse the direction of motion of the machine to bring the parts back to their starting position.

Having thus described an embodiment of 35 this invention it should be evident to those skilled in the art that various changes and modifications might be made therein without departing from its spirit or scope as defined by the appended claims.

We claim:

1. In a machine of the class described, a bolster over one face and edge of which a side of leather may be placed, means for clamping the leather against said edge, and means acting during a bodily movement thereof relative to said bolster for drawing and stretching the leather from said edge across said face.
2. In a machine of the class described, a bolster over one face and edge of which a side of leather may be placed, means for clamping the leather against said edge, and leather working elements movable bodily relative to said bolster and acting on the leather on said face during such movement.
3. In a machine of the class described, a bolster over one face and one edge of which a side of leather may be placed, means for clamping the leather against said edge, and means acting during a bodily movement thereof relative to said bolster for progressively pressing said leather against said face and rubbing down its exposed surface in a direction to stretch and work the leather away from said clamping means.
4. In a machine of the class described, a bolster on which leather may be supported, means for clamping the leather to said bolster, leather working mechanism, and means for moving said bolster and mechanism simultaneously and in opposite directions to effect treatment of the leather by said mechanism.
5. In a machine of the class described, a bolster on which leather may be supported, means for clamping the leather to said bolster along one edge, leather working mechanism, means for relatively traversing said bolster and mechanism, means for holding said mechanism and bolster in operative relation to effect treatment of the leather when said mechanism moves in a direction from said clamped edge, and means for rendering said holding means inoperative on the reverse direction of traverse.
6. In a machine of the class described, a bolster on which leather may be supported, means for clamping the leather to said bolster, leather working instrumentalities including a fluted roller, means for rotating said roller, and means for effecting simultaneous traverse in opposite directions of said bolster and roller to cause said roller to act on the leather.
7. In a machine of the class described, a bolster on which leather may be supported, means for clamping the leather to said bolster, leather working instrumentalities including a fluted roller, means for rotating said roller, means for effecting simultaneous traverse in opposite directions of said bolster and roller, means for pressing said roller against the leather on one face of said bolster during the relative direction of traverse in which said roller recedes from said clamping means, and means for rendering said pressing means inoperative during the opposite direction of relative traverse.
8. In a machine of the class described, a bolster on which leather may be supported, means for clamping the leather to said bolster, leather working instrumentalities including a ribbed pressure plate, and means for effecting simultaneous traverse in opposite directions of said bolster and roller to cause said roller to act on the leather.

site directions of said bolster and plate to cause the ribs of said plate to press the leather against said bolster and rub the surface thereof.

5. In a machine of the class described, a bolster on which leather may be supported, means for clamping the leather to said bolster, leather working instrumentalities including a ribbed pressure plate, means for effecting simultaneous traverse in opposite directions of said bolster and plate, means for causing the ribs of said plate to press against the leather in the direction of relative traverse to cause the leather to be 10 worked and stretched away from said clamping means, and means for rendering said causing means inoperative during the opposite direction of relative traverse.

10. In a machine of the class described, a bolster on which leather may be supported, means for clamping the leather to said bolster, leather working instrumentalities including a fluted roller and a ribbed pressure plate, means for rotating said roller, and 20 means for effecting relative traverse between said bolster and instrumentalities to cause said roller and pressure plate to engage and work the leather over the face of said bolster from said clamping means.

30. 11. In a machine of the class described, a bolster movable upwardly and downwardly and constructed to support leather, leather working mechanism, and means for moving said mechanism in a direction opposite to that of said bolster in proper relation to act 35 on the leather supported thereon.

12. In a machine of the class described, a bolster movable upwardly and downwardly and constructed to support leather, leather 40 working mechanism, and means for moving said mechanism in a direction opposite to that of said bolster in proper relation to act on the leather supported thereon during one direction of relative traverse and out of 45 active relation thereto during relative traverse in the opposite direction.

13. In a machine of the class described, a bolster on which leather may be supported, means for clamping the leather to said bolster, leather working mechanism, means for effecting a relative traverse between said bolster and mechanism, means for holding said mechanism against the leather as said mechanism moves away from said clamping 55 means, and means for rendering said holding means inoperative during its movement in the opposite direction.

14. In a machine of the class described, a bolster movable in an upwardly and rearwardly inclined path, said bolster when at its lowest position being substantially vertical to receive work over its upper edge, means for tilting said bolster substantially into the plane of said path as it starts to 60 move upwardly therein, a member with

which the upper edge comes into clamping engagement to clamp the work thereon and so hold it during the major portion of the movement of said bolster, and work treating mechanism positioned to treat the work on 70 said bolster during said movement.

15. In a machine of the class described, a bolster movable in an upwardly and rearwardly inclined path, said bolster when at its lowest position being substantially vertical to receive work over its upper edge, 75 means for tilting said bolster substantially into the plane of said path as it starts to move upwardly therein, a member with which the upper edge of said bolster comes into clamping engagement to clamp the work thereon and so hold it during the major portion of the movement of said bolster, work treating mechanism positioned to treat the work on said bolster during said 80 movement, and means for moving said mechanism downwardly across the face of said bolster as said bolster is moved upwardly.

16. In a machine of the class described, a substantially upright bolster member over 85 the upper edge of which a side of leather may be placed, means to clamp the leather along said edge to said bolster, and leather-working instrumentalities engaging and working the leather at opposite sides of said 90 clamp.

17. In a machine of the class described, a substantially upright bolster member over 95 the upper edge of which a side of leather may be placed, means to clamp the leather along said edge to said bolster, and leather-working instrumentalities engaging and working the leather at opposite sides of said 100 clamp and away therefrom.

18. In a machine of the class described, a member on which leather may be supported, a leather working member, means for relatively traversing said members, and means for holding one of said members in operative position relative to the other member 105 for working on the leather during one direction of relative traverse, said means also positively separating said members at the end of the traverse in said direction.

19. In a machine of the class described, a bolster on which leather may be supported, leather working mechanism, means for relatively traversing said bolster and mechanism, supports for said bolster and mechanism, means for holding said supports in a 110 position to permit the leather to be worked on during one stroke of the traverse, and means timed to separate automatically said supports at the end of said stroke.

20. In a machine of the class described, a bolster on which leather may be supported, leather working mechanism, means for relatively traversing said bolster and mechanism to work the leather during one stroke 115 thereof and to idle during the reverse 120

stroke, supports for the bolster and mechanism, and means timed to move one of said supports away from the other at the end of the working stroke and to move said support toward the other at the end of the idling stroke to bring said bolster and mechanism into operative relation.

21. In a machine of the class described, a bolster on which leather may be supported, leather working mechanism, means for relatively traversing said bolster and mechanism to work the leather during one stroke thereof and to idle during the reverse stroke, and a device for moving the bolster into operative relation with the leather working mechanism, said device including means for locking the bolster in said operative relation during the working stroke.

22. In a machine of the class described, a member on which leather may be supported, a member for working the leather, means for relatively traversing said members to work the leather during one stroke thereof and to idle during the reverse stroke, and means for locking said members in operative relation during the working stroke.

23. In a machine of the class described, a member on which leather may be supported, a leather working member, means for relatively traversing said members to work the leather during one stroke thereof and to idle on the reverse stroke, and means timed to move one of said members into operative relation to the other at the end of the idling stroke, to lock said member in operative relation to the other during the working stroke, and to remove said member from operative relation to the other at the end of the working stroke.

24. In a machine of the class described, a bolster on which leather may be supported, leather working mechanism, means for relatively traversing said bolster and mechanism, means for holding said mechanism and bolster in relative position to cause said mechanism to act on leather on said bolster during one direction of relative traverse and for holding them out of such relative position on the opposite direction of traverse, and means actuatable to move them out of said position at any time during said one direction of traverse.

25. In a machine of the class described, a bolster on which leather may be supported, leather working mechanism, means for relatively traversing said bolster and mechanism, means for holding said mechanism and bolster in relative position to cause said mechanism to act on leather on said bolster during one direction of relative traverse and for holding them out of such relative position on the opposite direction of traverse, and means actuatable to move them out of said position at any time during said one direction of traverse and to return them

to their starting positions of said one traverse direction.

26. A machine of the class described comprising a bolster over which leather may be supported, leather working mechanism, means actuatable to effect a relative traverse between said bolster and mechanism in both directions, means for automatically stopping the machine at the end of each return traverse, and means actuatable by the first mentioned means for holding said bolster and mechanism in position for said mechanism to act on leather on said bolster during the first relative direction of traverse and for holding them out of such position during the return direction of traverse.

27. A machine of the class described comprising a bolster over which leather may be supported, leather working mechanism, means actuatable to effect a relative traverse between said bolster and mechanism in both directions, means for automatically stopping the machine at the end of each return traverse, means for holding said bolster and mechanism in position for said mechanism to act on leather on said bolster during the first relative direction of traverse and to hold them out of such position during the return direction of traverse, and means actuatable at any time during the first direction of traverse for moving them out of such position.

28. A machine of the class described comprising a bolster over which leather may be supported, leather working mechanism, means actuatable to effect a relative traverse between said bolster and mechanism in both directions, means for automatically stopping the machine at the end of each return traverse, means for holding said bolster and mechanism in position for said mechanism to act on leather on said bolster during the first relative direction of traverse and to hold them out of such position during the return direction of traverse, and means actuatable at any time during the first direction of traverse for moving them out of such position and for returning them to stopped position.

29. In a machine of the class described, a pair of spaced parallel track beams each pivoted at one end, a bolster over which leather may be placed reciprocable along said track beams, leather working mechanism, and means for swinging the free ends of said track beams toward said mechanism and so holding them during one direction of traverse of said bolster in position to cause leather on said bolster to be operated on by said mechanism and for retracting said ends and so holding them during the opposite direction of traverse of said bolster.

30. In a machine of the class described, a pair of spaced parallel track beams each pivoted at one end, a bolster over which

leather may be placed reciprocable along said track beams, means to move said bolster, means acting after a predetermined extent of motion in one direction to reverse the direction of motion, leather working mechanism, and means for holding the free ends of said track beams swung toward said mechanism during said one direction of motion of said bolster and acting when the motion is reversed to move said free ends away from said mechanism.

31. In a machine of the class described, a pair of spaced parallel track beams each pivoted at one end, a bolster over which leather may be placed reciprocable along said track beams, means to move said bolster, means acting after a predetermined extent of motion in one direction to reverse the direction of motion, leather working mechanism, means for holding the free ends of said track beams swung toward said mechanism during one direction of motion of said bolster and acting when the motion is reversed to move said free ends away from said mechanism, and operator actuatable means for moving said free ends away from said mechanism and reversing the direction of motion of said bolster at any time during its movement in said one direction.

32. In a machine of the class described, a pair of spaced parallel track beams each pivoted at one end, a bolster over which leather may be placed reciprocable along said track beams, means to move said bolster, means acting after a predetermined extent of motion in one direction to reverse the direction of motion, leather working mechanism, means for holding the free ends of said track beams swung toward said mechanism during one direction of motion of said bolster and acting when the motion is reversed to move said free ends away from said mechanism, and means for stopping the machine after a predetermined extent of reversed motion of said bolster.

33. In a machine of the class described, a pair of spaced parallel track beams each pivoted at one end, a bolster over which leather may be placed reciprocable along said track beams, means to move said bolster, means acting after a predetermined extent of motion in one direction to reverse the direction of motion, leather working mechanism, means for holding the free ends of said track beams swung toward said mechanism during one direction of motion of said bolster and acting when the motion is reversed to move said free ends away from said mechanism, means for stopping the machine after a predetermined extent of reversed motion of said bolster, and operator actuatable means for moving said free ends away from said mechanism and reversing the direction of motion of said bolster at any time during its movement in said one direction.

34. In a machine of the class described, a pair of downwardly and forwardly inclined spaced parallel track beams, a carriage slideable on each of said beams, a bolster over which leather may be placed pivoted to said carriages, means for holding said bolster in substantially vertical position when said carriages are adjacent to the lower ends of said beams and for tilting said bolster rearwardly substantially parallel to said track beams as said carriages move upwardly, a clamp engaging leather placed over the upper edge of said bolster as said bolster reaches its tilted position and movable therewith during its subsequent motion, means for moving said carriages up said track beams to determined positions, means acting automatically when said carriages reach said positions to reverse their directions of motion, leather working mechanism past which said bolster is moved, and means acting when said bolster reaches its initial lowest position for stopping the machine.

35. In a machine of the class described, a pair of downwardly and forwardly inclined spaced parallel track beams, a carriage slideable on each of said beams, a bolster over which leather may be placed pivoted to said carriages, means for holding said bolster in substantially vertical position when said carriages are adjacent to the lower ends of said beams and for tilting said bolster rearwardly substantially parallel to said track beams as said carriages move upwardly, a clamp engaging leather placed over the upper edge of said bolster as said bolster reaches its tilted position and movable therewith during its subsequent motion, means for moving said carriages up said track beams to determined positions, means acting automatically when said carriages reach said positions to reverse their directions of motion, leather working mechanism past which said bolster is moved, means acting when said bolster reaches its initial lowest position for stopping the machine, and operator actuatable means for moving said free ends away from said mechanism and reversing the direction of motion of said bolster at any time before said carriages have reached said predetermined positions.

36. In a machine of the class described, a pair of downwardly and forwardly inclined spaced parallel track beams each pivoted at its upper end, a carriage slideable on each of said beams, a bolster over which leather may be placed pivoted to said carriages, means for holding said bolster in substantially vertical position when said carriages are adjacent to the lower ends of said beams and for tilting said bolster rearwardly substantially parallel to said track beam as said carriages move upwardly, a clamp engaging leather placed over the upper edge of said bolster as said bolster reaches its tilted position and movable therewith during its subsequent motion, means for moving said

carriages up said track beams to determined positions, means acting automatically when said carriages reach said positions to reverse their directions of motion, leather working mechanism past which said bolster is moved, means for holding the lower ends of said track beams forwardly during the upward motion of said bolster to cause said mechanism to act on the leather 10 and acting to move said lower ends rearwardly when the direction of motion is reversed, means acting when said bolster approaches its lowest position for swinging said lower ends forwardly, and means acting 15 when said bolster reaches its lowest position for stopping the machine.

37. In a machine of the class described, a pair of downwardly and forwardly inclined spaced parallel track beams each pivoted at 20 its upper end, a carriage slidable on each of said beams, a bolster over which leather may be placed pivoted to said carriages, means for holding said bolster in substantially vertical position when said carriages 25 are adjacent to the lower ends of said beams and for tilting said bolster rearwardly substantially parallel to said track beams as said carriages move upwardly, a clamp engaging leather placed over the upper edge

of said bolster as said bolster reaches its 30 tilted position and movable therewith during its subsequent motion, means for moving said carriages up said track beams to determined positions, means acting automatically when said carriages reach said positions to reverse their directions of motion, leather working mechanism past which said bolster is moved, means for holding the lower ends of said track beams forwardly during the upward motion of said bolster to 40 cause said mechanism to act on the leather and acting to move said lower ends rearwardly when the direction of motion is reversed, means acting when said bolster approaches its lowest position for swinging 45 said lower ends forwardly, means acting when said bolster reaches its lowest position for stopping the machine, and operator control means actuatable at any time during the upward motion of said bolster for causing 50 said track beam moving means to move said beams rearwardly, and to actuate said reverse means.

In testimony whereof we have affixed our signatures.

FREDERIC D. CLEMENT.
JOHN A. WHEELER, JR.
